UNITED STATES PATENT OFFICE.

LEVITT E. CUSTER, OF DAYTON, OHIO.

MEANS FOR CONTROLLING DIRIGIBLE TORPEDOES.

No. 913,814.

Specification of Letters Patent.

Patented March 2, 1909.

Application filed July 23, 1906. Serial No. 327,284.

To all whom it may concern:

Be it known that I, LEVITT E. CUSTER, a citizen of the United States, residing at Dayton, in the county of Montgomery and State of Ohio, have invented certain new and useful Improvements in Means for Controlling Dirigible Torpedoes; and I do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to new and useful improvements in wireless telegraphy, and more particularly relates to means for controlling the steering mechanism of floating bodies, such as a torpedo, balloon, etc.

The objects of the invention are to provide in a wireless telegraphy system for the above purpose, first; means comprising an auxiliary decoherer for positively insuring a reversal of the current in the motor by which the torpedo rudder is actuated through relays and other mechanism; secondly—means for preventing "Hertz waves" generated at other transmitting stations, influencing the motor-reversing mechanism; and thirdly—means for observing from a distance the direction and path of travel of the torpedo.

Preceding a detail description of the invention, reference is made to the accompanying drawings, of which—

Figure 1, is an illustration of well known appliances of a wireless telegraphy system or transmitting station. Fig. 2, is a diagrammatic view of the electro-mechanical mechanism of the torpedo. Figs. 3 and 4, are detail views of the decoherer and motor-reversing mechanism. Figs. 5 and 6, are detail views of the auxiliary decoherer. Fig. 7, is a rear view of a floating torpedo having lamps by which the direction and path of the torpedo may be observed from the transmitting station. Figs. 8-9 and 10, are diagrammatic views in details of the motor-reversing circuit. Figs. 11 and 12, are detail views of the switch through which the pilot lamps are controlled. Fig. 13, is a top plan view of a torpedo provided with my new appliances.

In a detail description of the invention,

similar reference characters indicate corresponding parts.

1 designates a torpedo which may be equipped with any means of propulsion, such for example, as an electric or compressed air-motor for driving the propeller 3. In the drawings, I have shown an electric motor 2. The torpedo 1 is equipped with a rudder 4 which is controlled by a motor 5 through gears 6 and worm gears 7, as shown in Fig. 13. The object of the gears is to reduce the speed of the motor 5 to a lower speed as required by the partial revolution of the rudder.

As shown in Fig. 2, the motor 5 is connected in series to a storage battery 6 through the reversing drum 7; the circuit is shown in Fig. 2 by a line consisting of dashes with one dot intervening between each two of said dashes. Engaging the reversing drum 7 are four brushes 8—9—10 and 11; the brush 8 is connected to one end of the motor field while the other end is connected to the brush 11 through the storage battery 6; the brush 9 is connected to one of the commutator brushes, 80 while the other commutator brush is connected to brush 10. It will therefore be seen that if the ends of the brushes 8 and 9 are joined, and likewise the ends of the brushes 10 and 11, there will be a closed circuit, and if means are employed to join the ends of the brushes 8 and 10 and likewise the ends of brushes 9 and 11, there will be a reversal of the current in the armature of the motor 5, and the direction of rotation of the 90 motor will be reversed. The reversing drum 7 is mounted on shaft 12 and consists of a cylinder of insulating material around the ends of which, are mounted two continuous bands or metallic rings 13 and 14, the former of which, is adapted to continuously engage the brush 8, and the latter of which is adapted to likewise engage the brush 11. Projecting from the ring 13 is an ear 15 adapted to engage the brush 9, and projecting from the ring 14 is a similar ear 16 adapted to engage the brush 10. The ears 15 and 16 are directly opposite each other so that each of said ears will be engaged by its respective brush 9 or 10 at the same time. The width of each of these ears is equal to one-fourth the diameter of the drum 7. Dimensionally opposite said ears 15 and 16 are two metallic plates 17 and 18 which are adapted to engage the respective brushes 9 and 10.

110

The width of these plates is also one-fourth of the diameter of the drum 7. The plate 17 is connected to the ear 16 by a connection 19 so that it receives current in the same direction as the brush 11, ring 14, and ear 16; the plate 18 is connected to the ear 15 by a connection 20 so that it receives a current in the same direction as the brush 8, the ring 13 and the ear 15. Referring to Figs. 8 and 9, these connections are shown diagrammatically; in Fig. 9, the brushes 9 and 10 are in engagement with their respective ears 15 and 16 and the brush 8 will receive current directly from the brush 9 while the brush 10 will receive current directly from the brush 11. If the drum 7 be given a half revolution, the brushes 9 and 10 will engage their respective plates 17 and 18 as shown in Fig. 8, and the brush 9 will receive current in an opposite direction from that shown in Fig. 9, through the plate 17, the connection 19, the ear 16 and the ring 14. The brush 13 will receive current in the same direction as in Fig. 9 through the ring 13, ear 15, the connection 20, the plate 18 and the brush 10. It will be noted that the direction of the current in the armature of motor 5 only, is reversed, as it is well known in the art that if the direction of the current in both the field and the armature were reversed, the direction of rotation of the armature would not be reversed. As hereinbefore stated, the ears 15 and 16 occupy one-fourth of the diameter of the drum 7 as do also the plates 17 and 18; the two intervening spaces between said ears and plates are occupied by insulating material.

It will be seen from Fig. 10, that when the brushes 9 and 10 rest upon the spaces, the circuit will be opened and the motor will be at rest. The reversing drum may also be constructed to accommodate a shunt wound motor. The means for rotating the reversing drum is described as follows: It has been hereinbefore stated, that the drum 7 is mounted on shaft 12, the latter being journaled in bearings 21 on the base 22. Mounted upon this shaft 12 is a ratchet wheel 23 engaged by a pawl 24 and retaining pawl 32, said ratchet wheel 23 being provided with any number of teeth which is a multiple of four. In the drawings, I have shown sixteen teeth in said wheel. The pawl 24 is actuated from the decoherer, and upon said decoherer being actuated, the drum 7 will be moved forward to the extent of one tooth of the ratchet wheel. It will be seen from the description of the reversing mechanism, that it is necessary to rotate the drum 7 one-fourth of a revolution to change the direction of current to the motor 5, and the purpose in providing a multiplicity of ratchet teeth for each change is to secure a certain amount of latitude from outside or foreign influences. When the torpedo mechanism is in operation and it is desired to change the condition of the motor

5, four pulsations are sent out from the transmitting station—Fig. 1. The drum 7 will be moved forward four teeth or one-fourth of a revolution, and the connections to the motor will be changed. If the receiving apparatus 70 or coherer receives the pulsation from any foreign influence, or Hertz waves from some other transmitting station, the drum 7 will be moved forward one tooth and the connections to the motor will not be changed owing 75 to the brushes 9 and 10 being still upon the ears 15 and 16 or plates 17 and 18 as the case may be. It will be understood that the greater the number of teeth on the ratchet wheel 23, the greater will be the freedom 80 from outside interference or influence. The pawl 24 is controlled by a spring 25, both of which are mounted on the armature 26 of the decoherer, see Figs. 3 and 4. The said armature is pivoted at 27, and the extent of its 85 movement is controlled by screws 28, a spring 29 maintaining said armature in an upward position. The armature is provided with a tappet 30 which is adapted to engage and decohere the coherer 31. Mounted 90 below said armature on the base 22 is a magnet 42 adapted to influence said armature. It will be seen that upon the magnet being magnetized the armature will be drawn down and the ratchet wheel 23 will be moved forward to the extent of one tooth. The decoherer may be used as a sounder in transmitting signals. I employ the well known form of coherer consisting of a glass tube having two terminals in close proximity and 100 between which are placed metallic filings. The tappet 30 provides the usual form of decoherer, but in practice, I have found that this form is not reliable, consequently, in my system I employ an auxiliary decoherer to 105 make positive the operations of decohering the filings. Mounted on a base 33 is a magnet 34 which is adapted to influence an armature 35 pivoted at 36 and the movement of which is regulated by screws 37; a spring 38 110 holds said armature in an upward position. This armature 35 is provided with a tappet 39 which is adapted to engage the coherer 31. Mounted on said armature is a leaf spring 40 which engages a screw 41 having 115 a platinum contact with said spring. It will be understood when the armature 35 is drawn down, the spring 40 will recede from the screw 41, and as the current which energizes the magnet 34 passes through this 120 spring and screw, the circuit will be broken, and as the spring 38 will immediately re-establish the circuit, there will be a continuous series of taps on the coherer 31 which will be continued until the circuit through the 125 coherer is destroyed. The magnet 42 of the decoherer and the magnet 34 of the auxiliary decoherer are connected in parallel to the relay 43 through battery 44; this circuit is shown in Fig. 2 by a line consisting of long 130

dashes; the relay 43 is of the well known form. The coherer 31 is mounted in any suitable manner and one of its terminals 45 is connected to a mast 46, and the other terminal 47 is connected to the ground 48. These connections carry the Hertz wave current and are shown in Fig. 2 as a continuous line. The terminals 45 and 47 of the coherer 31 are connected to the magnet 51 of the relay 43 through choke coils 49 and a battery 50 in the usual way; this circuit is represented in Fig. 2 by a line of short dashes.

In Fig. 1, I have shown the usual form of transmitting station in which the primary 15 coil 52 is connected in series with a key 53 and a battery 54; one terminal of the secondary coil 52' is connected to a mast 55 and the other to the ground 56. The said terminals are also connected to two metallic 20 globes 57 which are a suitable distance apart. Upon the primary circuit being closed by the key 53, a current of high potential is induced in the secondary coil causing a spark to pass between the globes 57. The passage of this 25 spark generates electric waves otherwise known as "Hertz" waves which influence the coherer 31 in such a manner that the resistance of the filings in the said coherer is reduced to an extent which allows a current 30 from the battery 50 to energize the magnet 51 of the relay 43. The choke coils 49 are of high resistance and compel the Hertz waves to travel through the coherer.

The means for observing the path and direction of the torpedo is described as follows: 35 Referring to Figs. 7 and 13, 58 designates a lamp mounted on a mast 46 on the torpedo; 59 is a similar lamp on the stern of the torpedo; these lamps are continuously burning 40 owing to their connection with a battery. Mounted on each side of the torpedo are two lamps 60 and 61 which are connected to a battery as shown in Fig. 2. The connection of these lamps is such that upon the motor 5 45 rotating in a certain direction, one of said lamps will burn and upon the motor being reversed, the other lamp will burn while the one previously burning will be extinguished. If the motor is at rest, neither of these lamps 50 will burn. From Fig. 13, it will be seen that the lamp 59 is in the rear of the lamp 58, consequently, if the torpedo is moving from the operator and the lamp 59 moves to the left of the lamp 58, the operator will observe 55 that the torpedo is going to the right, and if the lamp 59 moves to the right of the lamp 58, the reverse of the above is the case. By the aid of the lamps 60 and 61, the operator is enabled to know whether the mechanism 60 in the torpedo is responding to the pulsations sent out by the transmitting station. The mechanism through which these lights 60 and 61 are controlled is described as follows:

The connections are illustrated in Fig. 2, formed by a line of dashes with two dots intervening between each two of said dashes. 65 Mounted upon the shaft 62 of the steering motor 5, is an arm 63 having a carbon terminal 64—see Figs. 11 and 12. The arm 63 is provided with a spring 65 which presses 70 against the shaft 62; the friction between the spring 65 and shaft 62 is sufficient to turn the arm 63 with said shaft, so that in whatever direction the shaft 62 rotates, the position of the arm 63 is determined. The 75 carbon terminal 64 is adapted to engage either of two carbon terminals 66 and 67 on each side of the shaft 62; the carbon terminal 67 is connected to one of the terminals of the lamp 60, and the terminal 66 is connected to one of the terminals of the lamp 61. The other terminal of the lamp 61 is connected to the circuit 68, and the other terminal of the lamp 60 is connected to the motor circuit at 70. The carbon terminal 64 on the arm 80 85 63 is connected through the shaft bearing of the motor 5, to the circuit at 69. When the terminal 64 engages the terminal 66 as shown in Fig. 2, the current coming from the battery will pass through the connection 69; 90 the shaft 62; the arm 63; terminal 64; terminal 66; lamp 61; connection 68; brush 10; ear 16; ring 14; brush 11; to the battery, whereas, if the terminal 64 engages the terminal 67, the current from the battery 95 will pass through connection 69; shaft 62; arm 63; terminal 64; terminal 67; lamp 60; connection 70; brush 9; plate 17; connection 19; ring 14; brush 11, to the battery.

It will be understood that if the brushes 100 9 and 10 engage the insulation between the ears 15 and 16, and plates 17 and 18, the lamps 60 and 61 will not burn, and it will be further understood that said lamps will not short circuit any part of the motor owing 105 to their being of the necessary resistance.

I claim as my invention, ~

In a system of wireless telegraphy, a transmitting station, a coherer, a single-tapping decoherer engaging said coherer, an auxiliary-vibrating decoherer engaging said coherer and adapted to create a series of vibrations in the coherer while the current is passing through said coherer until said current is interrupted, and means whereby said 110 single-tapping decoherer and said auxiliary-vibrating decoherer are actuated when the coherer receives impulses from the transmitting station. 115

In testimony whereof I affix my signature, 120 in presence of two witnesses.

LEVITT E. CUSTER.
